CLAIM

The ornamental design for an air freshener with jar and fabric, as shown and described.

DESCRIPTION

FIG. 1 is a perspective view of an air freshener with jar and fabric showing our new design;

FIG. 2 is a top plan view thereof;

FIG. 3 is a front view thereof, the sides and rear being substantially identical; and,

FIG. 4 is a bottom plan view thereof.

The cross hatching in FIGS. 1-4 represents conventional fabric and is understood to extend uniformly throughout the areas represented.
